FISHING LURE

George Dennis Pinnell, 1000 Ave. C, Dodge City, Kans.

Filed Aug. 5, 1963, Ser. No. 76,102

Term of patent 14 years

(Cl. D31—4)

Fig.1.

Fig.2.

Fig.3.

Fig.4.

FIG. 1 is a side elevational view of a fishing lure, showing my new design;

FIG. 2 is a top plan view thereof;

FIG. 3 is a bottom plan view thereof; and

FIG. 4 is a front elevational view.

The side of the lure not shown is identical in appearance to the side shown.

The dominant features of my design reside in the portions shown in full lines. It is to be understood that the criss-cross pattern continues throughout the unshaded areas.

I claim:

The ornamental design for a fishing lure, as shown and described.
